(57) **CLAIM**

The ornamental design for a combined power bank with mobile phone stand, as shown and described.

DESCRIPTION

FIG. 1 is a front, right side and top perspective view of a combined power bank with mobile phone stand, showing my new design;

FIG. 2 is a front, left side and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the combined power bank with mobile phone stand, shown in an environment of use.

The broken lines are shown for the purpose of illustrating both parts of the combined power bank with mobile phone stand as well as environment subject matter. None of the broken lines form no part of the claimed design.
